(57) **CLAIM**

The ornamental design for mounting arm for display stand, as shown and described.

DESCRIPTION

FIG. 1 is a perspective view of a first embodiment of a mounting arm for display stand, showing my new design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof;

FIG. 8 is a perspective view of the first embodiment shown with additional environment;

FIG. 9 is a perspective view of a second embodiment of a mounting arm for display stand, showing my new design;

FIG. 10 is a front view thereof;

FIG. 11 is a rear view thereof;

FIG. 12 is a left view thereof;

FIG. 13 is a right view thereof;

FIG. 14 is a top plan view thereof;

FIG. 15 is a bottom plan view thereof; and,

FIG. 16 is a perspective view thereof with additional environment.

The broken lines immediately adjacent to the shaded areas depict the bounds of the claimed design, while all other broken lines are directed to environment. The broken lines form no part of the claimed design.

1 Claim, 16 Drawing Sheets
